C. G. HABERMAN

SWING

Filed March 11, 1927

CHARLES G. HABERMAN,

INVENTOR.

BY *Harold C. Shippman*

ATTORNEY.

UNITED STATES PATENT OFFICE.

CHARLES G. HABERMAN, OF BOURBON, INDIANA.

SWING.

Application filed March 11, 1927. Serial No. 174,675.

This invention relates to swings, and the principal object of the invention is to provide a swing wherein the seat is hingedly connected at one end to an upright member and the handle portion pivotally connected thereto, so that the person while swinging, can provide an uneven motional effect.

A further object is to provide a swing of the above described nature wherein the foot board is pivotally mounted in the upright in combination with the handle portion and by the twisting of the handle portion and foot board a wiggly-wobbly effect will be caused to the swing while in motion.

15 A further object is to provide a means for attaching the swing to a cross bar, so as to cause only a reasonable amount of friction against the swinging motion.

With the foregoing and other objects in view, as will appear as the description proceeds, the invention consists of the novel construction, combination and arrangement of co-operating elements as hereinafter more specifically set forth, claimed and shown in 25 the accompanying drawing forming a part of the present application, in which:

Fig. 1 is a perspective view of one form of my invention.

Fig. 2 is a modified form.

30 Fig. 3 is a front view of one of the attaching members.

Fig. 4 is a sectional view taken on the line 4—4 of Fig. 3.

Like numerals of reference designate corresponding parts throughout the different views.

5 indicates the seat of the swing, which is narrowed at its forward end, so as to allow the legs of the person to extend downwardly to the foot board 6. The forward end of the seat 5 is bifurcated as at 7. 8 is a single upright having its lower end engaged to the foot board 6 and the upright 8 fits into the bifurcated portion 7 of the seat 45 5 and is retained thereto by the transverse pin 9. 10 indicates the handle supported at the upper end of the upright 8 by the screw 11, the handle being turnable on the screw. 12 indicates the front flexible connections secured at one end near the outer end of the foot board 6 and extending upwardly through the corresponding end of the handle 10. 14 indicates the flexible connection having its one end secured through 55 the rear portion of the seat 5. The upper ends of the flexible connections 12 and 14

each connect to a link 15 mounted on the cross bar 16. This link 15 is preferably made of strong sheet metal having an annular looped portion. The ends of the metal 17 meet together at the lower side and protrude outwardly therefrom. These ends may be attached together by the rivets 18 and an opening 19 is formed through the protruding ends 17, through which opening 65 the flexible connections 12 and 14 are tied. At approximately one-third the distance around the link 15, an opening 20 is cut in the metal and on each side of this opening 20, as at 21, the metal is bent outwardly, 70 while the portion next the outer edge is bent inwardly, as at 23. The pin 22 is seated across the link 15 and is held between the outwardly bent portions 21 and the inwardly bent portions 23. A bearing 24 is mounted 75 on the pin 22. Fig. 4 shows the spaced position of these bearings 24 relative to the cross bar 16, which bearings 24 roll on the cross bar 16 when the swing is in motion. 25 indicates collars for holding the link 15 against 80 longitudinal movement on the cross bar 16, which collars are fixedly positioned thereto by the set screws 26.

Referring to Fig. 2 showing the modified form, the construction is practically the same as in Fig. 1 with the exception that the foot board 6 is held to the lower end of the upright 8 by the rod 27, which extends longitudinally through the upright 8. The lower end of the rod 27 is squared to fit into the 90 square opening 28 in the foot board 6 and the nut is suitably threaded on to the threaded end 29 of this rod 27. The handle 10 is in a like manner attached to the upper end. By having the rod 27 extended longitudinally through the upright 8, the handle 10 and the foot board 6 are secured together to turn in unison.

With a person on the seat 5, the swinging motion may be started and greatly increased by operation of the handle 10 and the foot board 6. When the desired swing is obtained the handle 10, or the handle 10 and the foot board 6, may be turned in either direction, which turn will cause a wiggly-wobbly motion to the swing and will cause considerable excitement and amusement.

The foregoing specification and annexed drawings disclose the preferred embodiment of my invention, but it is to be understood that minor changes may be resorted to in the commercial adaptation of my invention with-

out departing from the scope of the invention as hereinbefore claimed.

What I claim as new is:

1. A swing, comprising a seat, having a narrowed forward end; said forward end being bifurcated; an upright pivotally connected to said bifurcated end; a foot board mounted on the lower end of said upright; a handle pivotally mounted at the upper end of said upright; a flexible connection extending through each end of said handle and having their lower ends respectively connected to the ends of said foot board; a flexible connection having its lower end connected to the rear end of said seat.
- 10 2. A swing, comprising a seat, having a narrowed forward end; said forward end

being bifurcated; an upright pivotally connected to said bifurcated end; a foot board mounted on the lower end of said upright; 20 a handle pivotally mounted at the upper end of said upright; a flexible connection extending through each end of said handle and having their lower ends respectively connected to the ends of said foot board; a flexible connection having its lower end connected to the rear end of said seat and a means interconnecting between said handle and said foot board, so that said handle and said foot board may be turned in unison relative to 30 said upright.

In testimony whereof, I affix my signature.

CHARLES G. HABERMAN.
